UNITED STATES PATENT OFFICE.

PETER ALLINIO, OF EL CERRITO, CALIFORNIA.

AEROPLANE.

1,292,415.

Specification of Letters Patent. Patented Jan. 28, 1919.

Application filed November 1, 1917. Serial No. 199,628.

To all whom it may concern:

Be it known that I, PETER ALLINIO, a subject of the King of Italy, residing at El Cerrito, in the county of Contra Costa and State of California, have invented certain new and useful Improvements in Aeroplanes, of which the following is a specification.

My invention relates to that class of aeroplanes in which pendulous swaying structures, by their tendency to maintain their equilibrium, are made the motive for automatic control or balance.

In a previous Patent No. 1062074, issued to me May 20, 1913, I disclose a machine of this class, in which provision is made for the automatic control of both the lateral and longitudinal balance, the former being due to the movement of the ailerons by the pendulous action of the freely suspended car, and the latter being effected by the fore and aft swinging movement of the seat acting on the elevator plane of the horizontal tail-plane or stabilizer.

My present invention relates more particularly to the longitudinal balance, and it consists in the novel means for automatically operating the elevator planes of the tail-plane or stabilizer, together with certain details of construction, all of which I shall hereinafter fully describe by reference to the accompanying drawings, in which—

Figure 1 is a side elevation of my aeroplane.

Fig. 2 is a front view of the same, the propeller being omitted.

Fig. 3 is a perspective view showing the hanging of the seat, and its several connections.

Fig. 4 is a detail of the skeleton frame of the car.

Fig. 5 is a detail of means for hinging the members of the planes.

1 indicates the main planes, a biplane being herein shown for the sake of illustration, though it may be a monoplane or a multi-plane as the case may be. These planes 1 are connected rigidly by uprights 6, and the plane-structure is suitably tied up to or connected with the upper and lower cross bars 4 and 5 of an A-frame 2, which rises above the upper plane and has in its top a cross bar 3. This A-frame 2 lies at the front and back of the planes 1 at their transverse middle, as seen in Fig. 2.

7 is a car, hung pendulously for lateral swinging, by a frame 8, from the top cross bar 3 of the main-plane frame 2, the movement of the car being limited by an arcuate bracket 9 secured to the base of the hanger-frame 8, (see Fig. 2) which bracket slidably engages the lower ends of the main-plane frame 2.

10 are the ailerons. These are hinged at 11, Figs. 1 and 2, to the rear side of the upper main plane, at each end thereof, as seen in Fig. 2. To automatically operate these ailerons, to effect the lateral balance, I have connections substantially similar to those disclosed in my previous patent, above referred to, and which may be briefly described as follows:

14 in Fig. 2 is a line made fast at one side of a foot frame 13 of the car-hanger frame 8 which foot frame carries the ground wheels 12. Thence the line passes to a pulley 15 in the left extremity of the upper plane 1, and thence to a guide pulley 15' and thence around a drum 16 mounted revolvably on the cross bar 3 of the frame 2. Thence the line passes to a guide pulley 17' and thence to a pulley 17 in the right extremity of the plane, and thence to the other side of the foot-frame 13 to which it is secured. Thus by the relative lateral movement of the car and main planes, a rotary movement will be transmitted to the drum 16. This movement of the drum is made to operate the ailerons. Each of the latter has secured to it an arm 18 projecting above and below it (see Fig. 1). A line 19 is secured to the top of one of these arms and thence extends to a guide pulley 20 and thence around a drum 16' on the same hub with the drum 16 but of smaller diameter, and thence about a pulley 21, and to the top of the arm 18 of the opposite aileron, Fig. 2. A second line 22, suitably guided at 23 and 24, Fig. 2, and passing under the plane lengthwise, is secured to the lower ends of the arms 18 of both ailerons. It will now be seen that as the drum 16 is oscillated, it will, through the lines 19 and 22, cause the simultaneous opposite movements of the ailerons, and these movements, due to the difference in diameters of the drums 16 and 16' will be opposite to and differentiated from the movements of the main planes, which is, of course, essential to their proper function.

25 is the motor, 26 is the propeller, 27 is the radiator, 28 is the gasoline tank, and 29 are the ground skids. The automatic control of the longitudinal balance of the present improvement is as follows:—

Supported by guys 30 from the cross bar 3 of the main frame 2 is the horizontal tail plane 31, extending from the rear of the car.

Hinged to the rear edge of this plane at 10 32 (Fig. 1) is the elevator plane 33. There are two of these elevator planes, one beside the other; one only being here shown in side elevation of Fig. 1. Each elevator plane is provided with an arm 34 extending above 15 and below it, which arm is braced by guys 35.

Within the car 7, is the aviator's seat 37, carried by a platform or base board 36. Referring now, particularly to Fig. 3, in conjunction with Fig. 1, it will be seen that the 20 seat-base-board 36 is suspended for free swinging movement fore and aft, by hangers 38 suspended from brackets 39 of the car.

To the rear end of the seat-base-board 36 is made fast a line 40, which as seen in Fig. 25 1 emerges from the shell of the car and is fastened to the top of the arm 34 of the elevator plane 33. There are, of course, two of these lines 40, as shown in Fig. 3, one for each elevator plane. To the front of the 30 seat-base-board 36 is attached a turn-buckle 41 from the extremity of which extend two lines 42, each to a front guide pulley 43. These lines thence extend rearwardly, and emerging from the car shell, as seen in Fig. 35 1, pass to and are secured to the lower ends of the arms 34 of the elevator planes 33. 36 is a guide to prevent side swing of the seat.

It will now be seen that as the seat 37 40 swings under its equilibrating action, the elevator-planes will be automatically raised or lowered to perform their usual functions and to maintain the longitudinal balance.

In my previous patent, hereinbefore referred to, the fore and aft movement of the seat was communicated to the elevator plane through connections comprising a pivoted vertically disposed lever, the upper end of which projected relatively far above the seat. Experience has shown that this is not 45 good construction, in that it is not compact and is too much exposed. In the present arrangement, the contrary is true, because all the connections are well depressed, are not 50 exposed, and are compact. The arrangement also works in well with the connections for operating the rudder, as will now be explained.

44 in Fig. 1 are vertically disposed direct- 60 ing planes, to which the vertical rudder 45 is hinged along the line 46.

Secured pivotally at 47 to the front of the seat-base-board (Fig. 3) is the cross foot-lever 48. From the extremities of this 65 lever pass lines 49, which are directed by

guide pulleys 50, one to either side of the rudder 45, whereby said rudder is operated.

51 in Fig. 1 is a foot-shield on the car. In order to initially adjust the angle of the main planes with respect to the plane of 70 their travel, I provide the adjusting bolts 52, shown in Fig. 1. By this adjustment I am enabled to set the machine for the desired angle of ascent.

In Fig. 4 I have shown a portion of the 75 skeleton frame of the car 7. This frame comprises a plurality of cross ribs 53, one only being shown, and V shaped longitudinal ribs 54 let into the cross ribs. Between the longitudinal ribs, the cross ribs are 80 grooved out on a concave arc as shown at 55. The fabric covering, not shown, when fitted over this frame, will under the pressure of the wind belly in on these concave arcs with a uniform contour extending the 85 entire length of the boat and will not present abrupt shoulders and ridges as would be the case if the cross ribs were not cut out, for in such case the fabric would belly in between the longitudinal ribs in a series of 90 pockets between the cross ribs, leaving ridges at said cross ribs.

In Fig. 5, I show a form of hinge connection for the several members of the planes, which is well adapted for aeroplanes, in that 95 it avoids metal work.

56 indicate the adjacent frames of two members. These are covered with fabric 57, which is stitched at 58 between the frames. This connection is adapted for the joint between the ailerons and main plane, the joints between the tail plane and the elevator planes, and the joint of the rudder.

I claim:—

In an aeroplane, the combination of the 105 main-plane; a car; a horizontal tail-plane; a pair of side by side elevator planes hinged to the tail-plane, each carrying a cross-arm; an aviator's seat-platform; hangers freely suspending said platform within the car for 110 a fore and aft swinging movement; a pair of lines connecting with the rear end of the platform, and thence extending rearwardly through the side walls of the car and connected one to one end of the cross bar of one 115 of the elevator planes and the other to one end of the cross bar of the other elevator plane; a line secured to the forward end of the platform; a pair of branches from said line extending forwardly; a pair of fixed 120 guides carried by the car forward of the platform and around which said branches respectively pass, and said branches thence extending rearwardly through the side walls of the car and secured respectively to the 125 other ends of the cross bars of the elevator planes; a vertically disposed rudder hinged to the car; a foot cross-lever pivoted to the forward end of the aviator's seat-platform; a pair of lines connected respectively with 130

the ends of the cross lever and thence directed rearwardly above the car to either side of the rudder; lower guides for said lines carried by the rear of the seat-platform; and upper guides lying in the pivotal axis of the platform, over which said lines pass in their course to the rudder.

In testimony whereof I have signed my name to this specification in the presence of two subscribing witnesses.

PETER ALLINIO.
